[57] CLAIM

The ornamental design for a dispensing container for pharmaceutical diluents or the like, substantially as shown in the drawings.

DESCRIPTION

FIG. 1 is a front elevation of a dispensing container for pharmaceutical diluents or the like showing my new design;

FIG. 2 is a side elevation thereof;

FIG. 3 is an elevation as seen from the side opposite FIG. 2;

FIG. 4 is a top plan view thereof; and

FIG. 5 is a bottom plan view thereof.

Fig. 1.

Fig. 2.

Fig. 3.

Fig. 4.

Fig. 5.
